UNITED STATES PATENT OFFICE.

ANTON C. EGGERS, OF NEW YORK, N. Y., ASSIGNOR TO THE GOODYEAR'S INDIA RUBBER GLOVE MANUFACTURING COMPANY, OF SAME PLACE.

SYRINGE.

SPECIFICATION forming part of Letters Patent No. 659,470, dated October 9, 1900.

Application filed June 6, 1900. Serial No. 19,236. (No model.)

To all whom it may concern:

Be it known that I, ANTON C. EGGERS, a citizen of the United States, residing in the city of New York, borough of Brooklyn, State 5 of New York, have invented certain new and useful Improvements in Syringes, of which the following is a specification.

This invention relates to an improved syringe of that class in which a compressible bulb is used for pumping the liquid through the nozzle of the syringe. Heretofore the bulb was connected with valves at both ends and connected directly with a flexible tube leading to the sinker and a flexible tube leading 15 to the nozzle. This was attended with some inconvenience in manipulating the bulb.

My invention is designed to furnish a more convenient syringe in which the manipulation of the bulb is facilitated and a regular 20 pumping action is kept up in a reliable manner.

The invention consists of a syringe in which the elastic bulb is provided with a single opening connected with a T-shaped connecting-piece, in which two valves are arranged, one 25 for the inlet-tube and the other for the nozzle-tube, said double-valved T-shaped piece permitting the arrangement of the bulb at one side of said tubes, and thereby the more convenient handling of the bulb.

In the accompanying drawings, Figure 1 represents a side elevation of my improved syringe. Fig. 2 is an enlarged central longitudinal section through the detachable T-shaped piece connecting the bulb with the flexible tubes leading to the sinker and nozzle, respectively; and Fig. 3 is a vertical transverse section on line 3 3, Fig. 2.

Similar letters of reference indicate corresponding parts.

Referring to the drawings, A represents a bulb which is made of elastic material and closed with the exception of a single opening a, which receives a nipple b of a T-shaped 45 connecting-piece B, which is provided at opposite ends with two additional nipples b' b'', the nipple b' connecting with a preferably-flexible tube C, leading preferably to the sinker D, while the opposite nipple b'' is connected by a preferably-flexible tube C' with the nozzle E, as shown in Fig. 1. The T-shaped

connecting-piece is composed of a center portion b³, which is made integral with the nipple b and which is provided with a central channel b⁴, communicating with the nipples b' b'', and a channel b⁵ at right angles thereto passing through the nipple b into the bulb A. The central portion b³ of the T-shaped piece B is provided with short exteriorly-threaded ends or necks b⁶ b⁷, to which the interiorly-threaded nipples b' b'' are screwed home against the center portion b³. Leather or other washers w are interposed between the nipples b' b'' and the center portion b³, as shown in Fig. 2. The tubular neck b⁶, connecting 65 with the nipple b', is provided with radial slits s of considerable depth, while the short tubular neck b⁷, that forms connection with the nipple b'', is provided with a transverse pin p. The slits s of the tubular neck b⁶ are 70 for the purpose of permitting the water to pass through the same when the inlet-valve F, which is smaller in diameter than the valve-chamber, is opened under the suction of the bulb A, so that the liquid can pass through 75 the sinker D and flexible tube C into the bulb during the expansion of the same. The inlet-valve F is located on a seat f of the nipple b', its stem extending into the nipple, while the head of the valve presses on the 80 slotted face of the short tubular neck b⁶, when the liquid is sucked around the valve into the bulb. The outlet-valve F' is located near or adjacent to the valve-chamber in the short tubular neck b⁷, its stem being located in the 85 connecting-channel b⁴ of the center piece b³. When the bulb is compressed, the liquid in the same is forced through the channel b⁵ of the nipple b and the central channel b⁴ of the center piece b³ around the valve F', which is 90 smaller in diameter than the valve-chamber, and is pressed against the diametrical retaining-pin p and through the nozzle to the place of use.

The operation of my improved syringe is as 95 follows: When the bulb is compressed, the inlet-valve F is closed and the outlet-valve F' opened. Under the expansion of the bulb the suction in the same causes the liquid to be lifted through the sinker and flexible tube 100 C, so as to open the inlet-valve F and permit the liquid to pass into the bulb. The next

compression of the bulb presses the inlet-valve to its seat, so as to interrupt the flow of liquid through the same, and forces the liquid in the bulb through the outlet-valve F' and 5 flexible tube C' and nozzle to the place of use. This alternating action of the valves is repeated, and thus the effective working of the syringe kept up.

The T-shaped piece B by which the bulb 10 is connected with the flexible tubes connecting the sinker and nozzle, together with the two inlet and outlet valves in the same, permits the arrangement of the bulb at right angles to the connecting-piece sidewise of the 15 tubes, so that the syringe can be worked with much greater convenience than when the bulb is located in line with the flexible supply-tubes and is connected at opposite ends with the same. This is a great advantage in the 20 manipulation of the syringe, as it brings the bulb within convenient reach for the proper working of the syringe.

As the valves are located in the connecting-piece the construction of the bulb of the 25 syringe is greatly simplified, while the valves

are within easy reach for cleaning or repairing and reassembling.

Having thus described my invention, what I claim as new, and desire to secure by Letters Patent, is—

A T-shaped connecting-piece for a syringe, the same consisting of a center portion having a nipple extending at right angles therefrom, short exteriorly-threaded tubular necks at opposite ends of said center portion, one 35 of said necks being provided with radial slits extending from the bore to the outside of the neck, and the other with a valve-retaining device, nipples, interiorly threaded, screwed onto said necks, an inlet-valve in the inlet- 40 nipple, and an outlet-valve in the opposite neck, substantially as set forth.

In testimony that I claim the foregoing as my invention I have signed my name in presence of two subscribing witnesses.

ANTON C. EGGERS.
